UNITED STATES PATENT OFFICE.

JAMES R. RIPLEY, OF MEMPHIS, TENNESSEE.

DRY-KILN.

No. 877,736.

Specification of Letters Patent.

Patented Jan. 28, 1908.

Application filed August 29, 1907. Serial No. 390,651.

To all whom it may concern:

Be it known that I, JAMES R. RIPLEY, citizen of the United States, residing at Memphis, county of Shelby, and State of Tennessee, have invented certain new and useful Improvements in Dry-Kilns, of which the following is a specification, reference being had therein to the accompanying drawing.

This invention relates to a dry kiln adapted for drying lumber, wooden or other articles wherein they are subjected to a current of heated air for that purpose.

The invention has for an object to provide a novel and improved construction of air feeding device wherein the air is distributed over the material to be dried, and a circulation thereof maintained by which the moisture laden air may be removed from the kiln.

A further object of the invention is to provide means for condensing any steam rising from the material being dried and collecting the moisture therefrom so that it may be evaporated by the air circulation through the kiln.

Other and further objects and advantages of the invention will be hereinafter set forth and the novel features thereof defined by the appended claims.

In the drawings:—Figure 1 is a vertical section through the kiln; Fig. 2 is a top plan with parts in section and the roof removed from two of the suction chambers above the tracks. Fig. 3 is a reduced section on the line 6—6, Fig. 1.

Like numerals refer to like parts in the several figures of the drawings.

The numeral 10 designates the base or foundation of the kiln which is provided with the bearing 11 to carry the rotatable floor 12, said floor being provided with the radiating tracks 13 thereon adapted to be successively brought into alinement with the tracks 14 upon the receiving platform 15 disposed at one side of the kiln. The revolving floor is supported near its outer periphery in any desired manner, for instance, by bearing wheels 16 of ordinary construction and is adapted to be rotated by any suitable means, for instance, the cable or band 17 disposed in a groove upon the periphery and extending to a power windlass 18 driven from the shaft 19, as shown in Fig. 2. Surrounding this base and floor is the inclosing casing 20 of any desired material, preferably metal supported upon upright posts 21 and provided with one or more doors or closures in alinement with

the track 14. This may be of any desired construction, for instance, as shown in my Patent #772,962 of October 25, 1904, with which the present invention is adapted to be used in place of the air circulating means there shown.

The casing 20 is provided with the top or roof 22 having at its outer edge a series of radially disposed suction chambers 23. In the case of a circular kiln these chambers are of segmental shape and each thereof provided with the bottom wall 24 having a series of perforations 25 through which the moist air from the kiln is drawn. This bottom wall is inclined downwardly toward its center and from the center of the kiln to discharge at its outer end 25' into the gutter 26 carried by the inner face of the wall 20. These gutters collect the water and the moisture caught therein may be evaporated by the circulating air.

Extending upward from the outer portion of the suction chamber 23 is a triangular casing 27 which communicates with the conducting pipe 28, and the pipes from the several chambers extend to the central suction dome 29 from which the pipe 30 extends to any suitable suction device.

Communicating with each of the suction chambers 23 is a condensing stack 31 provided at its upper end with a discharge aperture 32 and the apertured cap 33 by which the discharge may be opened or closed as desired. The steam passing upward from the lumber collects in this stack and is there condensed by the atmosphere surrounding the same and the water therefrom drains into the gutter as before described.

The heated air for the purpose of drying is introduced with or without pressure through the conducting pipe 34, the inner end 35 of which is disposed in a vertical plane at approximately the axial center of the floor and is there surrounded by the telescoping sleeve 100 36 carried by the distributing head 37. Within this head a cone 38 is disposed so that the air is deflected outward in an even degree and discharged at the periphery 39 of the head so as to be directed into immediate contact with the material carried by the cars 40 and 41, traveling on the tracks 13. The former of these cars is adapted to carry supporting racks for thin stock, and the latter car may carry similar material but is used simply to properly space the racks and prevent contact thereof with each other due to

the radiating disposition of the tracks which closely approach each other at the center of the kiln. This car 41 is preferably of wedge shape, as shown in Fig. 6, for the purposes described. This air distributing head is mounted for vertical movement upon the conducting pipe in any suitable manner, one form of which may comprise the arms 42 connected by the rods 43 with a band 44 supported by hangers 45 from a lifting band 46 to which a cable 47 is connected. This is carried over the bearing rollers 48 and 49 to an operating device for continuously reciprocating the distributing head. A form of this device is shown in Fig. 1 where the rod 50 is mounted to reciprocate in keepers 51 carried by the frame 52 connected by the pitman 53 with the crank gear 54 which meshes with the pinion 55 upon the shaft of the driving gear 56.

Under some conditions it is desirable to introduce steam through the distributing head, particularly in case of fire or when the sap in the stock is to be killed before drying. This may be accomplished by a steam pipe 57 having its inner end 58 disposed downward in the heat conducting pipe 35 so that the discharge of steam therethrough is made laterally through the head similarly to the air discharge therefrom.

The introducing track 14 may be provided with any desired connections, for instance, the laterally disposed tracks 59 upon which a car may be switched by means of the turntable 60, as shown in Fig. 2.

In the operation of the invention the truck when filled with material to be dried is introduced into the kiln and the rotatable platform turned so as to load the kiln with successive cars, and the material may be unloaded in a similar manner. The heated air is introduced through the distributing head which may be continuously raised and lowered or reciprocated so as to distribute the air directly on all parts of the material, and owing to its position on the car passes between the material held thereon so as to thoroughly dry all parts thereof and avoid any warping owing to a more intense heat at one point than another when incomplete drying is caused. The heated air causes dampness to rise from the stock and this is blown toward the outlet and following the casing wall rises through the perforated plate 55 into the suction chambers from which it is drawn by the connections described. In this manner the stock is not "case hardened," but a natural drying is effected. If it be desired to kill the sap in the stock before drying or to extinguish any accidental fire in the kiln this may be accomplished by the steam pipe connection through which steam may be introduced into the distributing head, and the steam which collects in the suction chamber rises to the stack where it is con-

dened by the atmosphere and the water therefrom flows to the gutter from which it is evaporated by the air circulation established through the kiln.

While this invention has been described in connection with lumber drying it may be used for laundry or other purposes where it is desired to distribute the heated air introduced and maintain a circulation to remove moisture laden air from the kiln.

Having described my invention and set forth its merits, what I claim and desire to secure by Letters Patent is:—

1. In a dry kiln, a casing, an air conducting pipe extended therein, and a distributing device carried by said pipe and movable vertically therein to traverse the material to be dried.

2. In a dry kiln, a casing, an air conducting pipe extended therein, a distributing head, and means for vertically reciprocating said head.

3. In a dry kiln, a casing, a heat conducting pipe therein, a distributing head slidably mounted upon said pipe, and means for reciprocating said head.

4. In a dry kiln, a casing, a heat conducted pipe therein, a distributing head slidably mounted upon said pipe, arms extending from said head, operating rods extending through the top of the kiln from said arms, and means connected with said rods for continuously reciprocating the head.

5. In a dry kiln, a casing, a heat conducting pipe therein, a horizontally disposed distributing head having a discharge at its periphery, and a collar telescoping upon said pipe, and a deflecting cone within the head disposed beneath the discharge from said pipe.

6. In a dry kiln, a casing, a heat distributor disposed centrally thereof, means for vertically moving said distributor within the casing, a suction chamber disposed above the casing, and having communication therewith, and a platform within the casing between said distributor and the outer wall of the casing.

7. In a dry kiln, a casing, a heat distributor disposed centrally thereof, a suction chamber disposed at the edge of said casing, a discharge pipe from said suction chamber, a rotatable platform disposed within said casing, and a condensing stack communicating with said suction chamber.

8. In a dry kiln, a casing, a heat distributor disposed centrally thereof, a suction chamber disposed at the edge of said casing, a discharge pipe from said suction chamber, a rotatable platform disposed within said casing, a condensing stack communicating with said suction chamber, a centrally depressed floor for said suction chamber, and a collecting gutter disposed to receive the discharge from said floor.

9. In a dry kiln, a casing, a heat distributor disposed centrally thereof, a suction chamber disposed at the edge of said casing, a discharge pipe from said suction chamber, a rotatable platform disposed within said casing, a condensing stack communicating with said suction chamber, a centrally depressed floor for said suction chamber, a collecting gutter disposed to receive the discharge from said floor, and means for vertically reciprocating said heat distributor. 5
10. In a dry kiln, a casing, a heat distributor disposed centrally thereof, a suction chamber disposed at the edge of said casing, a discharge pipe from said suction chamber, a rotatable platform disposed within said casing, a condensing stack communicating with said suction chamber, a centrally depressed floor for said suction chamber, a collecting gutter disposed to receive the discharge from said floor, and means for vertically reciprocating said heat distributor. 10
15. In a dry kiln, a casing, an air inlet thereto, suction chambers disposed at the top thereof and each provided with a depressed floor having openings therein, a casing extending transversely of the suction chambers at one end thereof, and a suction pipe leading from said casing. 15
20. In a dry kiln, a casing, an air inlet thereto, suction chambers disposed at the top thereof and each provided with a depressed floor having openings therein, a casing extending transversely of the suction chambers at one end thereof, a suction pipe leading from said casing, and a gutter disposed at the inner wall of the kiln casing to receive the discharge from said floor. 20
25. In a dry kiln, a casing, a series of suction chambers disposed at the top thereof and provided with openings communicating with the casing, a central dome suction pipes extending from said chambers to a central dome, and a hot air inlet communicating with said casing. 25
30. In a dry kiln, a casing, a series of suction chambers disposed at the top thereof and provided with openings communicating with the casing, a central dome suction pipes extending from said chambers to a central dome, and a hot air inlet communicating with said casing. 30
35. In a dry kiln, a casing, a series of suction chambers disposed at the top thereof and provided with openings communicating with the casing, a central dome suction pipes extending from said chambers to a central dome, a hot air inlet communicating with said casing, condensing stacks communicating with the suction chambers, and a steam inlet communicating with said casing. 35
40. In a dry kiln, a casing, a series of suction chambers disposed at the top thereof and provided with openings communicating with the casing, a central dome suction pipes extending from said chambers to a central dome, condensing stacks communicating with the suction chambers, a steam inlet communicating with said casing, and an air intake communicating with said steam pipe. 40
45. In a dry kiln, a casing, a series of suction chambers disposed at the top thereof and provided with openings communicating with the casing, a central dome suction pipes extending from said chambers to a central dome, condensing stacks communicating with the suction chambers, a steam inlet communicating with said casing, and an air intake communicating with said steam pipe. 45
50. In a dry kiln, a casing, a series of suction chambers disposed at the top thereof and provided with openings communicating with the casing, a central dome suction pipes extending from said chambers to a central dome, condensing stacks communicating with the suction chambers, a steam inlet communicating with said casing, and an air intake communicating with said steam pipe. 50
14. In a dry kiln, a casing, a series of suction chambers disposed at the top thereof and provided with openings communicating with the casing, a central dome suction pipes extending from said chambers to a central dome, a hot air inlet communicating with said casing, condensing stacks communicating with the suction chambers, a steam inlet communicating with said casing, and a cap damper disposed upon the upper ends of said condensing stacks. 55
15. In a dry kiln, a casing, an air inlet thereto, suction chambers disposed at the top thereof and each provided with a depressed floor having openings therein, a casing extending transversely of the suction chambers at one end thereof, and a suction pipe leading from said casing. 60
16. In a dry kiln, a casing, an air inlet thereto, suction chambers disposed at the top thereof and each provided with a depressed floor having openings therein, a casing extending transversely of the suction chambers at one end thereof, a suction pipe leading from said casing, and a gutter disposed at the inner wall of the kiln casing to receive the discharge from said floor. 65
17. In a dry kiln, a casing, a centrally disposed heat distributing device therein, means for moving said device vertically and a truck provided with means for supporting material to be dried between the distributing device and casing. 70
18. In a dry kiln, a casing, a heat distributing device disposed centrally therein, means for reciprocating said device vertically and an air suction device communicating with the top of the kiln at the outer edges thereof. 75
19. In a dry kiln, a casing, a heat distributing device disposed centrally therein, an air suction device communicating with the top of the kiln at the outer edges thereof, a rotatable platform beneath said distributing device, and means for reciprocating said device vertically. 80
